CLOTHES WASHING MACHINE

John A. Castricone, Peoria, Ill., assignor to
 Altorfer Bros. Company, Peoria, Ill., a corpora-
 tion of Illinois

Application February 14, 1946, Serial No. 647,565

22 Claims. (Cl. 68—53)

1

This invention relates to domestic washing machines, and particularly to a washer incorporating a new washing principle or process wherein a unidirectionally movable displacement dasher creates the washing action without any axial rotation or oscillation as commonly used in vaned-agitator or impeller-type machines.

Although axially rotating or oscillating vaned-agitator machines are the most popular type of washers on the market at the present time, it is recognized that they are hard on clothes because of the heavy axial rotating contact of the vanes on the clothes. This is particularly true under large-batch loading conditions when one or two garments riding on the vanes may transmit the full force of the driving mechanism on practically the full load of clothes. Under such conditions, the power transmitted is often double the normal power input. Furthermore, when large or long garments are loaded and one end or section is caught on an axially rotating vane while the balance of the garment is entwined through the batch, the pull on such a garment often tears it. For instance, careful housewives do not wash lace curtains with batches of clothes in axially rotating vane washers.

Because of the uneven power requirements of agitator-type washers due to the clothes "riding the vanes," such washers must employ heavy expensive gear cases, back-gearred for speeds between 50 to 100 R. P. M. and capable of transmitting 100% overloads for short periods of time. The standard $\frac{1}{4}$ H. P. washing machine motor employed on such a machine must be capable of transmitting $\frac{1}{2}$ H. P. periodically.

It is the particular object of the present invention to provide a thoroughly effective washing action wherein cyclic toroidal rolling water currents are created in a throbbering action inwardly toward the dasher at the upper portion thereof and downwardly therealong and outwardly and upwardly at the lower portion thereof, and by a unidirectionally movable dasher having no fixed axial rotation which causes the clothes to be forced outward at the lower end of the dasher and to be drawn inward and downward at the upper end of the dasher.

I designate the clothes contacting and water circulating means as a "dasher" to differentiate it from the conventional "agitator" or "impeller," in order to divorce its displacement action without powered axial rotation from the power-driven pump-like radially-rotating vaned-impeller or its similarly powered axially-rotated oscillating agitator.

2

Another object is to provide an improved high speed unidirectionally movable dasher means having projecting vanes or the like for contacting clothes but without power-driven axial movements which would injure the clothes.

5 A further object is to provide a unidirectionally movable washer mechanism wherein the clothes are distributed evenly around the tub by an orbital movement of the dasher with respect to the tub wall and while they are being slowly rotated relative thereto in loose condition floating in the wash water.

10 The machine is designed to incorporate a unidirectional driving means actuating a dasher in an orbital path producing reactionary forces within the wash water that cause a predetermined continuous action or cyclic toroidal current flow of such wash water together with the clothes therein, and wherein such currents are produced by throbbering pulsations of the water, depending upon the rotary speed of the unidirectional driving means.

15 In addition to the recirculating wash-water currents, it is an object of the invention to provide such recirculation in a predetermined direction and selected path. This is accomplished in one way by the character of movement imparted to the vanes on the dasher, which will produce a throbbering action in the bottom of the tub causing 20 an outward and upward cyclic motion of the clothes and a reactionary inward and downward movement along the upper portion of the dasher, producing a greatly improved washing action.

25 In its preferred form, the dasher surface contour is so shaped as to provide a continuous im- 30 perforate circumferential wall at the base portion of the dasher and with the vanes thereabove, making the most effective pumping action generic to the bottom zone of the tub at the area 35 of greatest hydrostatic pressure, whereby the currents of wash water are forcefully directed 40 radially outwardly from the base portion of the dasher and upwardly out of the space between the dasher base and the tub wall.

45 To augment the washing action and to prevent the clothes from hugging the main surface of the dasher, in which position the clothes would tend to dam the downward recirculation of water, the dasher is provided with a plurality of radially-spaced fins or vanes which act to maintain the clothes directly in the recirculating zone of the water without impairing the displacement dasher action.

50 It is a further feature of the present invention 55 to provide a dasher that is mounted for floating

or restrained axial rotation upon its supporting bearings and which moves bodily in an orbit with respect to its driving axis, the dasher being shaped to perform the displacement action which produces radially circulating toroidal water currents that definitely drive the clothes radially and in tumbling fashion within the water and in a direction toward the upper surface of the dasher and the vanes with the clothes sliding downwardly along the edges of the vanes of the dasher.

The action of the clothes and water moving generally radially toward the dasher and lightly contacting the same act normally to restrain it against substantial radial movement relative to the wall of the tub while turning on its own bearings. The dasher normally stands still on its axis while being moved in an orbit about its driving shaft, but upon contacting bunched clothes may rotate slowly to effect uniform disposition of the clothes around the tub wall. In this connection, the dasher may be constructed in various shapes having predetermined contours and a predetermined arrangement of vanes. Also, the dasher may include apertures in the body thereof to produce water-current puffs or jets effecting additional washing action.

Another object of the present invention is to provide, when needed, for maintaining the dasher against appreciable rotation on its axis while being moved in an orbit. This is accomplished preferably by providing a slip clutch mechanism operatively connected with the dasher and carried upon the fixed column providing the bearing structure for the dasher. This slip clutch mechanism acts normally to restrain the dasher from turning upon its mounted bearing axis while moving about the drive shaft. However, with this slip clutch mechanism, the dasher may assume various new operative axial positions with respect to its own axis anywhere within the 360 degrees of activity within the tub. Such automatically selected axes of operation normally will depend upon the loading of the machine which directly affects the washing action as determined by the number of articles of clothing within the tub and upon the sizes and weights thereof and their grouping during the operation of the washing machine. This restrained rotation of the dasher is specified as "floatable." It will be obvious that heavy loads will be subjected to more squeezing action than light loads. It is also worthy of careful note that the clothes are continually but slowly rotated around the tub which further effects the equal distribution of the clothes in the tub.

All other objects and advantages inherent in the washing process and machine of the present design hereinafter shall be referred to in the following detailed description having reference to the accompanying drawings forming a part of this specification.

In the drawings:

Fig. 1 is a diagrammatic side elevational view of the washing machine of the present invention having certain parts broken away and in section to illustrate the general details of construction thereof;

Fig. 2 is a plan view of the dasher per se as seen when removed from the machine;

Fig. 3 is a vertical transverse cross-sectional view of the main working parts of the machine and more specifically through the dasher structure and its mounting;

Fig. 4 is a horizontal cross-sectional view taken substantially along the line 4-4 in Fig. 3, to il-

lustrate the details of a preferred design of slip clutch mechanism employed in the present washer;

Fig. 5 is a plan view of the machine tub and dasher diagrammatically illustrating certain principles of operation thereof;

Fig. 6 is a horizontal cross-sectional view as taken substantially along the line 6-6 in Fig. 3;

Fig. 7 is a horizontal cross-sectional view as taken substantially along the line 7-7 in Fig. 3, to illustrate further details of construction of the dasher;

Fig. 8 is a sectional view through a dasher of the kind illustrated in the preferred construction of washing machine, but wherein the dasher is provided with apertures capable of creating water jets to assist vanes in creating the desired throbbing action in the lower portion of the tub;

Figs. 9 and 10 are plan and side views, respectively, of a rosette type of a dasher which may be used in place of other dashers for producing the washing action;

Figs. 11 and 12 are plan and side views, respectively, of another modified construction of dasher that is usable in the washing machine of the present design;

Figs. 13 and 14 are plan and side views, respectively, of still another form of dasher for use in this machine;

Fig. 15 is a partial perspective view of the dasher illustrating diagrammatically the water currents produced; and

Fig. 16 is a diagrammatic plan view thereof.

Fig. 1 illustrates a washer having a base 1, supporting a tub 2 provided with the usual lid 3. The tub has dasher mechanism 4 of the present design diagrammatically illustrated as mounted for operation substantially centrally of the washing tub 2.

A motor 5 is conveniently mounted within the base 1 of the washing machine to drive directly the dasher 4 through a belt drive 6 connecting the motor pulley 7 with the dasher driving pulley 8, and the latter is secured to the main drive shaft 9 of the dasher. Obviously, it is to be noted that the entire drive is unidirectional and extremely simple, with no reduction gearing or gear box, and only a minimum number of moving parts.

Referring now to Fig. 3, the shaft 9 is rotatably mounted in bearings 10 and 11 secured in spaced relationship in a center post 12. This center post 12 is provided with an annular crimp 13 that is confined between a tubular sleeve 14 and an annular base plate 15, such sleeve and plate being conveniently secured to the base of the tub in any desired manner.

The upper end of the shaft 9 is fixed rigidly to a cap 16 that is secured to and forms a part of a depending driving sleeve 17 which is concentrically disposed with respect to the shaft 9 and rotates upon a bearing 18 secured to and surrounding a portion of the sleeve 14. A crank pin 19 is secured to the cap 16 in offset relation to the axis of the shaft 9, producing an eccentric drive, but with the axis of said crank pin 19 preferably spaced inwardly from the periphery of the major portion of the length of the sleeve 17. The dasher 4 has a main body 20 provided with an upper bearing bushing 21 journaled on the crank pin 19 supporting the dasher 4 thereon for relative rotation about the axis of the pin 19.

The depending end of the driving sleeve 17 terminates in an eccentric 22 having a conically tapered bearing surface 23. A plurality of rollers

24 are journaled upon pins 25 mounted in a ring 26 which is secured by means of suitable screws 27 to the body 20 of the dasher. These rollers 24 are conically positioned to engage properly the surface 23 of the driving eccentric 22, and the central axis of the eccentric 22 is positioned in direct alignment with the axis of the crank pin 19 thereby determining the axial eccentricity of the entire dasher 4 in relation to the axial center of the drive shaft 9.

Figs. 6 and 7 better illustrate certain details of construction showing the eccentric mountings of the dasher with respect to the drive shaft. It is to be noted in Fig. 6 that there are three rollers 24 preferably equally spaced on 120 degree radial plane positions.

Referring now to Figs. 3 and 4, the dasher body 20 is shown as provided further with a bracket 28 having a roller 29 rotatably carried upon a pin 30 supported by the bracket 28. This roller engages a side face of an arm 31 forming a portion of the slip clutch mechanism indicated generally at 32 in Figs. 3 and 4. This slip clutch mechanism comprises a pair of oppositely disposed friction straps 33 and 34 which encircle and frictionally engage a stationary flanged brake sleeve 35 that is secured to the tubular sleeve 14 so as normally to be fixed against rotation. The strap 33 former an integral portion of the arm 31 as best seen in Fig. 4.

A pair of adjustable spring tensioning units 36 and 37 connect the straps 33 and 34 yieldably to urge such straps into a predetermined frictional contact with the brake sleeve 35, the spring units 36 and 37 having adjustable means to increase or decrease the spring tension or frictional resistance offered between the surfaces of the straps 33 and 34 and the brake sleeve 35 encircled by such straps.

With this construction, the arm 31 extends radially outwardly from the fixed slip clutch mechanism that offers a predetermined reactionary force through the arm 31 against the roller 29 of the dasher 4. This slip clutch mechanism 32 normally should be tightened sufficiently on the sleeve 35 so as to hold the dasher 4 against any appreciable axial rotation while, nevertheless, moving through its orbit on rotation of the drive shaft 9. If loosened slightly, the mechanism 32 will allow very slow axial rotation of the dasher.

The direction of rotation of the drive shaft 9 is indicated in Fig. 3, and this direction is such as to floatably abut the roller 29 against arm 31. The maximum movement of the roller 29 parallel to the arm 31 is determined by the amount of eccentricity of the dasher 4, which is from the full line position in Fig. 4, to the dotted line position. This restrains the normal back-and-forth travel of the bracket 28 and the adjacent portion of the dasher-supported roller 29. The other part of the body of the dasher performs a compound motion somewhat as shown in Fig. 5, which may be summed up as comprising a bodily eccentric or orbital motion of the entire dasher, accompanied by a non-rotation thereof relative to the tub under normal operation as floatably governed by the slip clutch mechanism.

As stated before, the slip clutch can allow the arm 31 to move in either direction, and the arm 31 is shown in Fig. 5 as shifted from the dotted line position to the dash-and-dot position at 40. This latter position is only an arbitrary angular displacement, it being obvious that the displacement of arm 31 may taken any radial position about the 360 degrees of operation of the dasher

slip clutch combination described or may revolve slowly therearound. Normally, through driving friction between the parts, the direction of pressure of the dasher against the arm 31 is clockwise.

In Fig. 5, the dasher is outlined as occupying one position, 41, which coincides with the position that the dasher 4 occupies in Figs. 1 and 3. Other successive positions at 90 degree displacements are indicated in Fig. 5, by the reference characters a, b and c, respectively. The corresponding roller positions of the roller 29 are indicated at 41', a', b' and c, respectively.

The shifting of the slip clutch mechanism 32 and the axial position of the dasher, as judged by the location of the bracket 28 and its roller 29, will be determined under different conditions of loading as they arise during the operation of the washing machine. Excessive bunching of clothes in one portion of the tub, producing a crowding or overloading condition, will tend to force the dasher and its roller against the slip clutch arm 31, which restrains rotation of the dasher, to relieve the stressed condition. This displacement will occur continually to shift the dasher about its own axis as the latter is being moved bodily through the unidirectional movement of the main driven shaft 9 and the eccentric driving arrangement. Under normal even-loaded conditions of the tub the mechanism will operate almost independently of the slip clutch.

Referring to Figs. 1 and 3, it will be noted that the dasher 4 is shown as provided with a smooth-surfaced portion 42 forming a continuous imperforate circumferential wall substantially vertically disposed and having a relatively large diameter with respect to the internal diameter of the tub 2. However, the enlarged portion 42 is spaced an appreciable distance from the wall of the tub so as not to interfere with the free cyclic movement of the clothes therebetween. At the same time this portion 42 extends down close to the bottom of the tub. The upper portion of the dasher 4 forms a column 43 of considerably smaller diameter than the diameter of the base portion 42.

The general contour and shape of the dasher, as viewed in Fig. 3, includes a plurality of radial vanes 44 extending from the base 42 to the upper end of the column 43 filling in the valley portion of the middle part of the dasher. These vanes 44 are supplemented by additional vanes 45 radially disposed between the vanes 44 to prevent clothes from hugging the body of the dasher and to increase the thridding action in the water.

Through its rotation (with respect to the center post) and eccentric motion (with respect to the tub wall), the dasher 4 creates rapid progressive thridding pulsations within the wash water creating submerged toroidal currents at a rapid rate determined by the rotational speed of the shaft 9, the base portion 42 of the dasher 4 imparting continuous radial water currents in a predetermined progression moving outwardly toward the tub walls at the bottom portion of the dasher and creating an inward suction and downwardly therealong at the upper portion of the dasher, to recirculate radially inwardly toward the dasher and downwardly along the varied columns and through the valley of the same, such currents substantially following the paths of the arrows indicated in Figs. 1, 3 and 15.

This action has been observed in actual operation not only with a dasher of the character

described above, but also with dashers of other construction but having radial vanes in position to be immersed in the water, and moved through an orbit at a relatively high velocity but of confined magnitude less than that which would cause a radial discharge of the clothes therefrom by centrifugal force. The preferred stroke is of the order of one-half inch from the center axis of the shaft 9 to the center axis of the bearing 19. The speed of the shaft 9 is preferably of the order of 180 to 240 R. P. M. These characteristics are described, however, merely as illustrative, and may be varied so long as the desired throbbing action is obtained without appreciable centrifugal force that would tend to force the clothes outward in the tub.

The action observed appears to be caused by the action of the vanes moved in the water by the orbital motion of the dasher. The character of the water action that appears to result therefrom is indicated by the arrows in Fig. 15. The action of the vanes moved in the orbit, as shown in full lines and in dotted lines in Fig. 16, acts on the water to cause a throbbing in the lower portion of the tub which will impart a suction force downwardly along the dasher and inwardly at the top thereof. This is observed to have the effect in actual use of drawing the clothes inwardly toward the upper portion of the dasher and downwardly therealong, thence outwardly and upwardly, in toroidal action and in loose condition, obtaining the maximum washing effect. At the same time the clothes are not wrapped around the dasher, nor hang on the vanes.

The orbital movement of the dasher 4 will act within the ring of clothes that forms therearound to cause a turn-over of the ring at the bottom portion of the dasher, constantly pushing out on the clothes at the lower inner sector of the ring, as the vanes 44 and the cylindrical portion 42 are moved outward and inward at any particular portion of the dasher by the orbital movement thereof. This action tends to turn-over the clothes in the ring and at the same time, due to the relatively narrow spacing of the vanes 44, not more than 90° from each other, to create the downward and inward circulation of water therebetween, as pointed out above, to increase this turn-over of the clothes, substantially in a continuous progressive manner around the dasher as the latter is moved through its orbit.

This produces a steady overturning of the clothes in the same direction as indicated by the arrows, and the wash water is forced through the clothes by reason of the high speed throbbing pulsations imparted to the water by the dasher, making the movement of the water considerably faster than the movement of the clothes to produce a very effective relative washing action to clean the clothes quickly in a short interval of time and with a minimum amount of wear upon such clothes to further enhance the intrinsic value of this washing process. The power input requirements of the mechanism are substantially uniform and lower than impeller-type washers. This is because there is no heavy "riding" of radially moving vanes and the elimination of inertia loads inherent in reversing mechanism.

The introduction of the radial vanes 44 and 45 prevents the clothes from hugging the dasher column and maintains sufficient clearance for the recirculation of the wash water downwardly along the columns of the dasher and toward the strong displacement throbbing action zone adjacent the base 42 that sends its rapidly radiating water

currents outwardly as described. Obviously, the vanes contribute to the washing action to produce a light rubbing action during the eccentric motion of the dasher. The clothes immediately adjacent the dasher are carried downwardly and around to follow the contour of the dasher as they move from the upper level toward the lower level with the recirculating water currents constantly changing during the eccentric action of the dasher relative to the tub wall.

Thus, the washing machine embodies a dasher having eccentric motion to move bodily the entire dasher in the path of the eccentric movement, and such dasher is restrained or floatably supported to rotate independently. The high speed frequency of the eccentric motion produces the diverging water currents off of the surface of the dasher and due to the character of the vanes thereon, the currents recirculate to move the clothes toward the tub wall for movement upwardly therealong and back toward the center portion of the machine and the dasher, whereat the currents again reverse themselves to move downwardly along the surface of the dasher carrying the clothes downwardly in a position somewhat straddling the individual fins for rubbing therealong while such clothes travel downwardly near the body of the dasher. Inasmuch as the pulsations are generally radially and evenly distributed, the clothes and wash water acquire only a slow circular motion within the tub.

Therefore, it is worthy of careful note that the combination of the radial vanes and rapidly pulsating water currents have the desirable effect of distributing the clothes evenly around the dasher so that all portions of the clothes batch are subjected to practically uniform washing treatment. With this in mind, the slip clutch mechanism 32 illustrated in Figs. 3 and 4, might be entirely omitted, if desired, to eliminate any form of mechanical control means. Without the slip clutch mechanism 32, the dasher is only acted upon by the clothes so that the loading and proximity of the clothes alone will control the movements of the dasher upon its own axis of rotation. Such clothes, however, have no effect whatever upon the bodily orbital motion of the dasher as the latter is positively driven by the unidirectional power drive means.

Other dashers may be substituted for the dasher body 20 illustrated as the preferred construction. Fig. 8 represents such a modified construction wherein the dasher body 20 is provided with a plurality of apertures 46 extending along certain sections thereof, as shown, leaving the lower pump action portion 42 of the dasher continuous and imperforate, as shown. The apertures 46 in this form produce a multitude of jets at one side of the dasher as indicated in Fig. 15. Thus, the washing action is further aided by the jets produced by the openings in the dasher and the radial flat vanes on opposite sides thereof. Obviously, the location and direction of the openings may be changed to suit certain conditions of operation and to obtain a predetermined result in conjunction with the main washing action produced by the eccentrically moving dasher as previously described.

The dasher illustrated in Figs. 9 and 10 is in the form of a rosette wherein the general contour thereof includes the radially-formed vanes 47. This dasher shows the vanes 47 as curving upwardly and inwardly from the base 48 of such dasher so that the greatest pressure area thereof exists near its bottom.

The dasher in Figs. 11 and 12 provides a cylindrical body 49 having the apertures 50 therein which terminate intermediate the length thereof to provide a solid base portion 51 which introduces the greatest pump action as hereinbefore referred to, the current water pressure being decreased along the apertured area thereof. This dasher is provided with vanes 52 shaped as shown and radially positioned as in the other forms of dasher.

Another modified construction of dasher appears in Figs. 13 and 14 which is generally provided with a conical body 53 having an enlarged base portion 54 tapering toward the reduced-diameter top portion 55. A plurality of radially disposed surface vanes 56 cover the surface portion of the dasher for enhancing the washing action as previously described. With this latter type of dasher, the greatest displacement pump action portion will be adjacent the base 54 creating a greater pressure zone than can be established along the upper portions of the same unit. The more forceful water current zone created by this dasher is enhanced by the fact that the hydrostatic head of the wash water varies with the depth thereof, placing the greatest water pressure adjacent the lower portion of the dasher body to be acted thereon for producing the recirculating water currents that act so efficiently to wash the clothes in the present machine and in a relatively short interval of time.

For removal of the dasher for replacement purposes, the upper end of the dasher body 28 is covered with a closure cap 57 which normally covers and houses a hand nut 58 which screws upon the upper threaded end of the stud 19 normally to hold the dasher in operative position with respect to its eccentric driving mechanism and to the tub. Removal of the cap 57 and loosening of the hand nut 58 will allow lifting the dasher body 28 out of the machine whenever removal is desired. Replacement thereof is simple and obvious.

To summarize the action of the washing principle herein presented, the machine includes a tub that may be round, square or of other shape in contour, a vanned dasher in said tub, a drive mechanism having eccentric supporting bearings to carry the dasher, with the dasher being freely or floatably supported upon such bearings to seek its own angular positions relative to its own axis, and wherein the drive mechanism forces the dasher to move about the drive shaft in an orbit at a predetermined rate of speed—generally much faster than axially rotating impellers or agitators.

In effect, the dasher actually rotates upon its own bearings at a rate of speed which causes it normally to stand still relative to the tub while the eccentric driving arrangement moves the dasher bodily through the orbit about the drive shaft. The action of the clothes moving radially inwardly toward and against the dasher and moving along the vanes thereon normally prevents rotation of the dasher relatively to its assumed angular placement upon its supporting bearings.

Bunching or off-balance grouping of clothes which may occur only during the initial loading of the machine, will act upon the dasher to automatically adjust themselves about the dasher under uniform water current pulsations to equally surround the dasher, thereby distributing the washing load. With this construction, the clothes actually maintain their equally distributed posi-

tions through the washing operation while the machine subjects all the clothes to the same cleansing action, which is a combination of slow rotation around the tub, and cyclic toroidal rolling in relatively faster water currents.

Changes in the exact construction and combination of parts of the washing machine and its embodied mechanism are contemplated. All such modifications and substitution of equivalent means in the design of the preferred construction shown and described shall be governed by the breadth and scope of the appended claims submitted herewith and defining the fundamental structure of the present invention.

What I claim is:

1. In a washing machine, a receptacle adapted to contain a body of liquid for washing fabrics therein, a dasher extending upwardly in the receptacle, said dasher having upwardly extending vanes on the periphery thereof, and means for operating said dasher in an orbital motion of small magnitude and relatively high velocity such that a cyclic toroidal rolling action is created in the liquid inwardly and downwardly at the upper portion of the dasher and outwardly and upwardly at the lower portion thereof, said vanes comprising relatively thin flat blades projecting radially from the periphery of the dasher and extending throughout the major portion of the length thereof, said dasher having perforations in the upper portion thereof between the blades.
2. In a washing machine, a receptacle adapted to contain a body of liquid for washing fabrics therein, a dasher extending upwardly in the receptacle, said dasher being approximately bell-shaped with an outwardly flaring imperforate rim portion at the lower end thereof and with an inwardly tapering side wall portion thereabove and of appreciably smaller diameter than said rim portion, vanes extending upwardly along the side wall portion above the rim portion, said side wall portion having perforations therein along the length thereof between the vanes, and means for operating said dasher in an orbital motion.
3. In a washing machine, a tub, a drive shaft projecting within the tub, a dasher eccentrically mounted on the drive shaft and having clothes clearance projections thereon to provide vertical water passageways adjacent the body of the dasher and associated with the shaft for bodily rotating movement around the shaft, and means to yieldably restrain the dasher against axial rotation during its orbital movement.
4. In a washing machine, a tub, a dasher in said tub, and drive mechanism for said dasher comprising a unidirectional drive shaft, driving means connected between said drive shaft and said dasher to bodily move the latter in an orbit about said drive shaft, and reactionary means connected with said dasher normally to hold the same in a predetermined angular position with said tub during operation, said reactionary means comprising a support, an arm projecting therefrom, and a roller on said dasher in position for abutting contact with said arm.
5. In a washing machine, a tub, a dasher in said tub, and drive mechanism for said dasher comprising a unidirectional drive shaft, driving means connected between said drive shaft and said dasher to bodily move the latter in an orbit about said drive shaft, and reactionary means connected with said dasher normally to hold the same in a predetermined angular position within said tub during operation, said reactionary means

comprising a fixed support, an arm, a roller connected with said dasher and having abutting engagement with said arm, and releasable slip clutch mechanism for mounting said arm on said support to allow automatic angular shifting of said arm and said dasher under unbalanced load conditions during the operation of said washer.

6. In a washing machine, a receptacle adapted to contain a body of liquid for washing fabrics therein, a dasher extending upwardly in the receptacle, said dasher having upwardly extending vanes on the periphery thereof, and means for operating said dasher in an orbital motion of small magnitude and relatively high velocity such that a cyclic toroidal rolling action is created in the liquid inwardly and downwardly at the upper portion of the dasher and outwardly and upwardly at the lower portion thereof, said dasher having perforations in the upper portion thereof between the blades.

7. In a washing machine, a tub, a shaft extending upwardly in the tub and rotatably mounted therein, a dasher extending upwardly in the tub about the shaft, means journaling the upper end portion of the dasher on the upper end portion of the shaft eccentrically thereof, and means surrounding the shaft at a point spaced downwardly from said journaling means adjacent the lower end portion of the dasher and having a bearing surface surrounding the shaft and journaling the lower portion of the dasher eccentrically of the shaft.

8. In a washing machine, a tub, a shaft extending upwardly in the tub, a drive sleeve telescoped over the shaft in the tub concentrically thereof and secured thereto for rotation with the shaft, a dasher extending about the drive sleeve, means journaling the lower end portion of the drive sleeve in the tub, and means journaling the dasher on the drive sleeve on an axis spaced inwardly of the periphery of the major portion of the length of the drive sleeve and eccentrically of the axis of the drive shaft for causing orbital movement of the dasher about the drive shaft, said journaling means including upper and lower bearings, and said lower bearing having a bearing surface extending about the drive sleeve.

9. In a washing machine, a tub, a shaft extending upwardly in the tub, a drive sleeve telescoped over the shaft in the tub concentrically thereof and secured thereto for rotation with the shaft, a dasher extending about the drive sleeve, means journaling the lower end portion of the drive sleeve in the tub, and means journaling the dasher on the drive sleeve on an axis spaced inwardly of the periphery of the major portion of the length of the drive sleeve and eccentrically of the axis of the drive shaft for causing orbital movement of the dasher about the drive shaft, said journaling means including upper and lower bearings, and said lower bearing having a bearing surface extending about the drive sleeve adjacent the lower end of the dasher.

10. In a washing machine, a tub adapted to contain a body of liquid for washing clothes therein, a drive shaft extending upwardly in said tub, and a dasher surrounding said shaft and journaled for free and independent rotation relative to said shaft and tub, said shaft being connected with the dasher eccentrically of the shaft for moving the dasher bodily in an orbit relative to the axis of the shaft, said dasher having a diametrically reduced upper portion and a diametrically relatively enlarged lower portion joined

thereto and tapered inwardly to said reduced upper portion.

11. In a washing machine, a tub adapted to contain a body of liquid for washing clothes therein, a drive shaft extending upwardly in said tub, and a dasher surrounding said shaft and journaled for free and independent rotation relative to said shaft and tub, said shaft being connected with the dasher eccentrically of the shaft for moving the dasher bodily in an orbit relative to the axis of the shaft, said dasher having an enlarged substantially cylindrical base portion of appreciable height with a diametrically reduced upper portion thereabove and rigid therewith and having inwardly inclined connecting portions therebetween.

12. In a washing machine, a tub adapted to contain a body of water for washing clothes therein, a drive shaft extending upwardly in said tub, and a dasher surrounding said shaft and journaled for free and independent rotation relative to said shaft and tub, said shaft being connected with the dasher eccentrically of the shaft for moving the dasher bodily in an orbit relative to the axis of the shaft, said dasher having a body with a diametrically enlarged base portion with a diametrically reduced upper portion thereabove and rigid therewith, and means projecting outwardly from the body and spaced at intervals around the body for holding the clothes spaced from the body during said orbital movement.

13. In a washing machine, a tub adapted to contain a body of water for washing clothes therein, a drive shaft extending upwardly in said tub, and a dasher surrounding said shaft and journaled for free and independent rotation relative to said shaft and tub, said shaft being connected with the dasher eccentrically of the shaft for moving the dasher bodily in an orbit relative to the axis of the shaft, said dasher having a diametrically enlarged substantially cylindrical base portion of appreciable height with a diametrically reduced upper portion thereabove and rigid therewith, and vanes spaced at intervals around said upper portion and extending downwardly substantially to the base portion and having inwardly inclined outer edges, said vanes being spaced apart circumferentially of the dasher not more than 90° from each other.

14. In a washing machine, a tub adapted to contain a body of water for washing clothes therein, a drive shaft extending upwardly in said tub, and a dasher surrounding said shaft and journaled for free and independent rotation relative to said shaft and tub, said shaft being connected with the dasher eccentrically of the shaft for moving the dasher bodily in an orbit relative to the axis of the shaft, said dasher being substantially bell-shaped and having outwardly extending relatively flat vanes on the periphery thereof, and spaced apart circumferentially of the dasher not more than 90° from each other, whereby the clothes are caused to move outwardly at the bottom of the dasher and inwardly at the top thereof during said orbital movement.

15. In a washing machine, a tub adapted to contain a body of water for washing clothes therein, a drive shaft journaled for rotation relative to the tub, an upwardly extending dasher surrounding the axis of the shaft and having a diametrically enlarged lower portion and a diametrically reduced upper portion, said shaft being connected with the dasher eccentrically of the shaft for moving the dasher bodily in an orbit rel-

ative to the axis of the shaft, and means for holding the dasher against rotation about its own axis during the movement thereof through the orbit, said holding means including means fixed relative to the tub with an outwardly extending portion, and means connected with the dasher and bearing laterally against said outwardly extending portion.

16. In a washing machine, a tub adapted to contain a body of water for washing clothes therein, a drive shaft journaled for rotation relative to the tub, an upwardly extending dasher eccentrically connected with the drive shaft for movement of the dasher bodily in an orbit relative to the axis of the shaft, said dasher having a diametrically enlarged lower portion and a diametrically reduced upper portion and surrounding the axis of said drive shaft, and means for restraining the dasher against rotation about its own axis during said orbital movement, said restraining means including means fixed relative to the tub with an outwardly extending portion, and means connected with the dasher and bearing laterally against said outwardly extending portion.

17. In a washing machine, a tub adapted to contain a body of water for washing clothes therein, a drive shaft journaled for rotation in the tub, a dasher surrounding the shaft and extending throughout the major portion of the height of the tub, said dasher having a body with a diametrically enlarged base portion and a diametrically reduced upper portion thereabove and rigid therewith and extending upwardly throughout the major portion of the height of the tub, and means spaced at intervals around said dasher and projecting outwardly from the body for holding the clothes away from the body, said shaft being connected with the dasher eccentrically of the shaft for moving the dasher bodily in an orbit relative to the axis of the shaft, and means for holding the dasher against rotation during the movement thereof through the orbit, said holding means including means fixed relative to the tub with an outwardly extending portion, and means connected with the dasher and bearing laterally against said outwardly extending portion.

18. In a washing machine, a tub adapted to contain a body of water for washing clothes therein, a drive shaft journaled for rotation in the tub, an upwardly extending dasher surrounding the axis of the shaft, said dasher being substantially bell-shaped and having downwardly extending relatively flat vanes on the periphery thereof and spaced apart circumferentially of the dasher not more than 90° from each other, said shaft being connected with the dasher eccentrically of the shaft for moving the dasher bodily in an orbit relative to the axis of the shaft, and means for holding the dasher against rotation about its own axis during the movement thereof through the orbit, whereby the clothes are caused to move outward at the bottom of the dasher and inward at the top thereof during said orbital movement, said holding means including means fixed relative to the tub with an outwardly extending portion, and means connected with the dasher and bearing laterally against said outwardly extending portion.

19. In a washing machine, a tub adapted to contain a body of water for washing clothes therein, a drive shaft journaled for rotation relative to the tub, a dasher surrounding the shaft and having a diametrically enlarged lower portion

and a diametrically reduced upper portion, said shaft being connected with the dasher eccentrically of the shaft for moving the dasher bodily in an orbit relative to the axis of the shaft, and means for yieldably holding the dasher against rotation during the movement thereof through the orbit.

20. In a washing machine, a tub adapted to contain a body of water for washing clothes therein, a drive shaft journaled for rotation relative to the tub, a dasher in the tub and eccentrically connected with the drive shaft for movement thereby in an orbit relative to the axis of the shaft, and means substantially fixed relative to the tub and forming an abutment in the path of movement of the dasher through the orbit for restraining the dasher against rotation about its own axis during movement thereof through the orbit.

21. In a washing machine, a tub adapted to contain a body of liquid for washing clothes therein, a drive shaft extending upwardly in said tub, and a dasher surrounding said shaft and journaled for free and independent rotation relative to said shaft and tub, said shaft being connected with the dasher eccentrically of the shaft for moving the dasher bodily in a circular orbit relative to the axis of the shaft, means to rotate said shaft at a speed of approximately between

30 180 and 240 cycles per minute, said dasher having a diametrically reduced upper portion and a diametrically relatively enlarged lower portion joined thereto and tapered inwardly to said reduced upper portion.

35 22. In a washing machine, a tub adapted to contain a body of liquid for washing clothes therein, a drive shaft extending upwardly in said tub, and a dasher surrounding said shaft and journaled for free and independent rotation relative to said shaft and tub, said shaft being connected with the dasher eccentrically of the shaft for moving the dasher bodily in a circular orbit relative to the axis of the shaft, said orbit having a radius approximately one-half inch in any direction from the center of the orbit, and means to rotate said drive shaft at a speed of approximately between 180 and 240 cycles per minute,

40 45 50 said dasher having a diametrically reduced upper portion and a diametrically relatively enlarged lower portion joined thereto and tapered inwardly to said reduced upper portion.

JOHN A. CASTRIONE.
